UNITED STATES PATENT OFFICE.

HERBERT C. COY, OF CHICAGO, ILLINOIS, ASSIGNOR TO VULCAN MFG. CO., OF CHICAGO, ILLINOIS, A CORPORATION OF ILLINOIS.

SHOE-POLISHING DEVICE.

1,383,189.

Specification of Letters Patent. Patented June 28, 1921.

Application filed February 18, 1920. Serial No. 359,548.

To all whom it may concern:

Be it known that I, HERBERT C. COY, a citizen of the United States of America, residing at Chicago, in the county of Cook and State of Illinois, have invented certain new and useful Improvements in Shoe-Polishing Devices, of which the following is a specification.

My invention relates to shoe polishing devices, particularly of the portable type; and the objects of my improvement are:

First, the provision of an improved construction intended for holding a strip of suitable material in proper position relative to the surface to be polished when the shoe is on the foot of the wearer;

Second, to provide a shoe polishing device having means to restrain slipping of the device relative to the floor or other support;

Third, to produce a device of the class hereinafter described having means to minimize slipping tendency of the shoe when in position for polishing on the device; and

Fourth, the production of a portable device for shoe polishing whereby to reduce manual effort required in operation and to increase the efficiency of the device.

With the above and other related objects in view, my invention consists in the novel features and the novel combination and arrangement of parts illustrated in the accompanying drawings forming a part of this specification, and particularly pointed out in the claim hereunto appended; it being understood that changes, variations and modifications in the details of the invention within the scope of the claim, may be resorted to without departing from the spirit or sacrificing any of the advantages.

40 In the drawings—

Figure 1 is a diagrammatic view of the device and position of parts when in use.

Fig. 2 is a perspective view of the portable polishing device.

45 Fig. 3 is a longitudinal section on line 3—3 on Fig. 2.

Fig. 4 is a cross section on line 4—4 on Fig. 3.

Similar reference characters refer to similar parts throughout the several views.

Described more in detail, the structure chosen to exemplify my improvement includes a base having a set of lower parallel rods 6, 7, sufficiently wide enough apart to

give a measure of stability, a set of upper parallel rods 8, 9, relatively closer together to afford a sufficiently stable rest for the shoe on the wearer, end pieces 10, 11, in fixed relation to both sets of said parallel rods and one or more rollers 12 rotatably mounted on said end pieces.

Among other things, for the purpose of avoiding injury to the surface of the floor or other support, and the further object of restraining slippage of the device relative to the floor or the shoe on the wearer relative to the device, the rods 6, 7, 8, 9, preferably are coated with india rubber in some form 13, 14, 15, 16. One method of accomplishing this is by employing india rubber tubing of sufficiently less cross section than the rods on which the tubing is to be mounted that it be under tension and not slip relative to the rod.

I do not limit my invention to the use of any substance for the purpose of restraining slippage of the device in relation to the floor or other support, nor do I intend to be limited to the employment of rubber when material for the purpose of preventing slippage or protection against marring of floor or other support is used.

Preferably the rollers 12, consist of a pair, but it is obvious one of such rollers, instead of two rollers, will give good results and therefore I do not limit my invention to use of two such rollers.

As herein the rollers are turned of metal and have what are termed convex flanges 17 near their ends. The pivots 18 are disposed in apertures 19 in end pieces 10, 11.

The lower parallel rods 6, 7, and the upper parallel rods 8, 9, herein, and the end pieces 10, 11, are secured together by means of screws 20.

In operation, as indicated, a polishing strip 21, denotes one manner of polishing the fore part of the shoe. The shoe of the wearer is placed upon the upper parallel rods, and the polishing strip 21 laid flat over the top of the shoe and the ends of the strip down inside between and under the two rods and upward and the ends held by the operator who sits erect and pulls easily, but rapidly, back and forth a few times over every part of the shoe to be polished.

By showing and specifically the embodiment herein of my invention, I do not intend

to restrict the range of equivalents more than is made necessary by the prior state of this art.

Having thus fully described my invention, 5 what I claim as new, and desire to secure by Letters-Patent, is—

In a shoe-polishing device, a base having a

set of lower parallel rods coated with rubber, a set of upper parallel rods coated with rubber, end pieces in fixed relation to both sets 10 of said parallel rods and a plurality of rollers rotatably mounted in said end pieces.

In testimony whereof I affix my signature.

HERBERT C. COY.
